DESIGN FOR A WELL-CURB.

SPECIFICATION forming part of Design No. 13,966, dated June 5, 1883.

Application filed February 13, 1883. Term of patent 14 years.

UNITED STATES PATENT OFFICE.

MARK R. DAYKIN, OF CLEVELAND, OHIO.

DESIGN FOR A WELL-CURB.

SPECIFICATION forming part of Design No. 13,966, dated June 5, 1883.

Application filed February 13, 1883. Term of patent 14 years.

To all whom it may concern:

Be it known that I, MARK R. DAYKIN, a citizen of the United States, residing at the city of Cleveland, Cuyahoga county, and State 5 of Ohio, have invented and produced a new and original Design for Well-Curbs, of which the following is a specification, reference being had to the accompanying photograph, forming a part thereof.

10 Figure 1 is a view in perspective of a well-curb of such shape as is used with a well-bucket. Fig. 2 is a view in perspective of a well-curb such as is used with a chain-pump, both figures showing my new design.

15 Heretofore well-curbs have usually been painted with a groundwork of one color, on which has sometimes been placed ornamental stripes, lines, &c.

In my new design the whole body of the 20 well-curb is painted to represent a Scotch plaid, with bars or stripes of equal width crossing each other not quite at right angles, but leaving the checks or blocks slightly diamond-

shaped and with the longest diagonal line vertical. The plaid is made of three shades of 25 the same general color, and arranged as follows, to wit: The bars or stripes running in either direction are alike, and every other bar is made of an equal number of blocks or checks of dark and medium shades alternately, while 30 the intermediate bars or stripes are made of an equal number of blocks or checks of medium and light shades alternately.

What I claim is—

The design for a well-curb, as herein shown 35 and described, the same consisting in painting a well-curb to represent a Scotch plaid, the plaid being represented by bars of equal width and of three different shades of the same general color, arranged as heretofore described. 40

In testimony whereof I sign this specification in the presence of two witnesses.

MARK R. DAYKIN.

Witnesses:

C. H. DORER,
GEO. W. KING.
